UNITED STATES PATENT OFFICE.

SAMUEL C. VAUGHN, OF CHARLOTTE, NORTH CAROLINA.

JOURNAL-BOX JACK.

Application filed April 18, 1921. Serial No. 462,387.

To all whom it may concern:

Be it known that I, SAMUEL C. VAUGHN, a citizen of the United States, residing at Charlotte, in the county of Mecklenburg and State of North Carolina, have invented new and useful Improvements in Journal-Box Jacks, of which the following is a specification.

This invention relates to improvements in journal box jacks and has for an object the provision of a jack of this character, by means of which the journal boxes of railway cars may be lifted for the removal and insertion of the usual wedges and brasses, without raising the car wheels.

An object of the invention is the provision of means rigidly secured to the jack for engagement with the end of the journal to prevent the latter from raising, the said means being constructed to engage journals of different sizes in a manner to prevent accidental displacement and without the necessity of adjustment.

Another object of the invention is the provision of a journal-box jack which, when in use, is arranged to one side of the vertical center of the journal to permit ready access to the interior of the box.

With the above and other objects in view, the invention further includes the following novel features and details of construction, to be hereinafter more fully described, illustrated in the accompanying drawings and pointed out in the appended claim.

In the drawings:—

Figure 1 is a sectional view of a journal bearing with the invention applied thereto.

Figure 2 is a horizontal sectional view taken on a line above the wedge.

Figure 3 is a section on the line 3—3 of Figure 1.

Figure 4 is an enlarged detail section on the line 4—4 of Figure 1.

Figure 5 is an elevation of a modified form of jack.

Figure 6 is an enlarged section on the line 6—6 of Figure 5.

Figure 7 is a view similar to Figure 5 showing a still further modified form of jack.

Figure 8 is a section on the line 8—8 of Figure 7.

Figure 9 is a front view illustrating the form of jack shown in Figure 1 with the offset feature eliminated.

Referring in detail to the drawings, where-

in like characters of reference denote corresponding parts, the jack is shown in connection with an ordinary journal bearing which includes a box 10, the usual brass bushing 11 and wedge 12. In the removal of the wedge and brass from the box, the latter is vertically lifted and it is desirable to provide some means for preventing the car axle and wheel from raising at the same time, in order that the journal and the bearing may be separated for the removal of the wedge and brass. It is further desirable that the parts be positively held so as to prevent slipping when the jack is in operation and for this purpose it is of importance that the engagement between the jack and the journal be positive so that accidental displacement will be prevented and danger of accident eliminated.

With this in view, the invention provides a jack which is formed of a substantially U-shaped member 13 which includes upper and lower substantially parallel arms 14 and 15, which are connected by a vertical bar 16. The arm 15 is provided with a threaded opening 17 for the passage of a screw 18, whose upper end is provided with a head 19 for engagement beneath the bottom of the journal box 10.

The arm 14 has rigidly secured to its free end a transversely arranged journal engaging member 19' having an arcuate groove 20 therein for the reception of a collar 21 which is located at the outer end of the car journal or axle 22. The journal engaging member 19' is adapted to engage over the vertical center of the journal so as to provide a direct downward thrust when the jack is operated to raise the journal box and owing to its construction will fit over collars of different sizes and at the same time provide a sure and positive grip, the flanges formed by the groove 20 engaging upon opposite sides of the collar.

In the operation of the jack, the screw 18 has mounted thereon a socketed member 23 which receives the screw, the latter at this point being provided with teeth 24 for engagement with oppositely extending spring dogs 25. One of these dogs engage the teeth 24 to rotate the screw 18 in one direction, while the opposite dog is engaged to provide for a rotation in the opposite direction, an adjustable stop 26 which is carried by the socketed member 23 providing for holding either of these dogs in an operative position.

An operating handle 27 may be inserted within the socketed member to provide proper leverage.

In order to permit easy access to the interior of the journal box, the bar 16 which connects the upper and lower arms 14 and 15 is offset as shown at 27' so that the said arm is disposed to one side of the vertical center of the bearing.

10 In the operation of the invention, the jack is positioned as illustrated in Figure 1 of the drawings and when the lever 27 is operated, the screw 18 will be rotated to raise the box 10, while engagement of the member 19 over the collar of the car journal or axle will prevent the latter from being raised. As before stated it is essential that during the operation of jacking up the box, the parts must be held in a positive manner to prevent slipping. This is provided for by having a rigid connection between the jack and the collar 21. This engagement of the collar and jack is thus prevented and any tendency of the jack to slip from beneath the 25 journal box is also prevented.

In the form of the invention shown in Figures 5 and 6, the screw 18 has mounted thereon a gear 28 which threadedly engages the screw. The screw also extends through a threaded opening provided in the lower arm 15' of the jack and through a similar opening formed in an arm 29 which extends from and is parallel to the outer end of the arm 15'. The gear 28 is positioned between the arm 15' and the arm 29 and when this gear is rotated vertical movement will be imparted to the screw 18. The rotation of the gear 28 is accomplished through the medium of a worm 30 which is mounted 30 upon a shaft 31, the latter being rotatable in bearings 32 extending from the arm 15'. The shaft 31 is provided at its end with an operating lever 33, which may have a ratchet engagement with the shaft 31 to provide for 35 rotating the latter.

40 In Figures 7 and 8, the construction is somewhat the same, except that instead of having the operating handle arranged adjacent the bar which connects the upper and lower arms of the jack, the said operating handle is disposed laterally or to one side of the outer end of the arm 15'. In this 45 form there is provided a beveled gear 34

which is engaged by a beveled pinion 35, the latter being carried upon a stub shaft 55 36 which is mounted in bearings 37 extending from the jack. The shaft 36 is provided with a ratchet engaged operating lever 38 to provide for rotating the same. Like the form of the invention shown in Figures 5 and 6, the form shown in Figures 7 and 8 has its shaft 18 threadedly engaging the gear 34 and the bearings provided in the arm 15' and the inwardly extending parallel arm 39.

50 In the form of the invention shown in Figure 9, the construction is similar in all respects to that described in connection with Figure 1, except that the bar 40 which connects the upper and lower parallel arms of the jack is arranged substantially in a line with the vertical center of the journal bearing and not offset as previously described.

55 The invention is susceptible of various changes in its form, proportions and minor details of construction and the right is herein reserved to make such changes as properly fall within the scope of the appended claim.

60 Having described the invention what is claimed is:—

A journal box jack comprising a substantially U-shaped member presenting horizontal upper and lower parallel bars connected by a vertical bar offset laterally with respect to the parallel bars, an integrally formed head depending from adjacent the free end of the upper bar and presenting a groove for the reception of the outer end of a car journal or axle, a bearing arm integral with the lower horizontal bar and extending inwardly from adjacent the outer free end thereof in spaced parallel relation to the upper face of the bar, a screw extending vertically through aligned openings in the said arm and lower horizontal bar, a gear positioned for rotation between the said arm and lower horizontal bar and having a central bore threadedly engaging the said screw, a shaft journaled longitudinally of the said lower bar in bearings 65 extended laterally from the lower bar, a worm 70 on one end of the shaft engaged with the said gear, and an operating lever at the opposite end of the shaft.

75 In testimony whereof I affix my signature.

SAMUEL C. VAUGHN.
